UNITED STATES PATENT OFFICE.

FRANCISCO CLARK, OF DURANGO, MEXICO.

ADJUSTABLE TUMBLER-LOCK.

1,366,161.

Specification of Letters Patent. Patented Jan. 18, 1921.

Application filed June 17, 1919, Serial No. 304,887. Renewed December 4, 1920. Serial No. 428,378.

To all whom it may concern:

Be it known that I, FRANCISCO CLARK, a citizen of Mexico, and a resident of Durango city, in the State of Durango and 5 Republic of Mexico, have invented a new and Improved Adjustable Tumbler-Lock, of which the following is a full, clear, and exact description.

This invention relates to a new and im- 10 proved lock and more particularly to a lock of the combination type.

The inventor is aware that heretofore there have been various constructions suggested for a combination lock, but such de- 15 vices have involved complicated constructions and the use of many parts and have necessitated the use of a key having a complicated construction in connection therewith, and further in the use of a combination 20 key with a lock, it has necessitated further movement of the key in order to release the locking mechanism after the key has been positioned in the keyhole. Such locks are easily rendered inoperative if dirt or 25 other particles become lodged in the keyhole, they being of such construction as to make it extremely difficult, if not impossible, to remove the same.

One of the objects of this invention is to 30 overcome the objections above noted in combination locks heretofore provided and to provide a lock of simple construction, hav- 35 few parts, compactly arranged, and which may be relatively inexpensive to manufac- ture.

A further object of this invention is to 40 provide a combination lock which may be actuated by the mere insertion of a key within the keyhole of the lock without fur- ther movement thereof.

A further object is to provide a combination lock having its parts so constructed and arranged that the mere insertion of a key therein will bring the mechanism of the 45 lock in such a position as will permit the latch or bolt member of the lock to freely move without further movement of the key.

Still another object of this invention is 50 to provide a lock so constructed as to make it impossible to use a master key thereon or to obtain an impression of any kind that will permit a key to be made to release the lock without having knowledge of the combination of the lock.

55 Still another object is to provide a combi-

nation lock, which is adapted to be used with a combination key which is positively held in position when the key is inserted in the keyhole without further movement thereof, and will permit the bolt or latch 60 member of the lock to be freely moved.

The above objects are substantially ac- 65 complished by providing in a combination lock a plurality of tumblers which prefer- ably are of uniform construction, having 70 positioned thereon a plurality of adjustable peg members so positioned that when a combination key is inserted within the keyhole, having ward members set to correspond with the setting of the pegs in the tumbler 75 members, a pathway will be afforded to permit free movement of the bolt or latch member of the lock. In the preferred construc- 80 tion a spring member is used to actuate the bolt member when the key is inserted, but if desired, a separate means may be pro- 85 vided for obtaining movement of the bolt member when the key is inserted in the keyhole.

A further object of this invention is to 80 provide a universal combination lock to be used with a combination key, it being uni- 85 versal in the respect that knowing the com- bination thereof any combination key to be used therewith may be changed to corre- 90 spond therewith, the lock being so con- 95 structed that the setting thereof may readily be changed to form a different combination and necessitate a resetting of the key there- for.

Other objects and advantages will be ap- 95 parent from the following description and the accompanying drawings in which simi- 95 lar characters of reference designate like parts in the several views.

Figure 1 is an elevation view of the lock 100 with the outer casing removed therefrom and showing the position of the bolt member as used with a spring slide door jamb.

Fig. 2 is a sectional view looking in the 100 direction of the arrows and taken on the line 2—2 of Fig. 1, with casing applied to the lock.

Fig. 3 is an elevation view of the lock 105 with the casing applied thereto showing the position of the keyhole and the ends of the tumblers.

Fig. 4 is a sectional view taken on the line 2—2^A of Fig. 1, but is shown with the key 110 in position, and casing in place.

Fig. 5 is a sectional view looking in the direction of the arrows and taken on the line 5-5 of Fig. 1.

Fig. 6 is a bottom plan view of Fig. 4 with 5 the lower casing removed, looking in the direction of the arrows and taken on the line 6-6 of Fig. 4.

Fig. 7 is an enlarged broken elevation 10 view of one of the tumbler members with the peg positioned therein.

Fig. 8 is a side elevation of Fig. 7.

Fig. 9 is a plan view showing a modification of the form of peg which may be provided for the tumblers.

15 Fig. 10 is a side elevation of Fig. 9.

Fig. 11 is a plan view of a bolt having a release to be actuated from inside the door thereon.

20 Fig. 12 is a front elevation view of Fig. 11.

Fig. 13 is a rear elevation of Fig. 12.

25 Fig. 14 is a fragmentary sectional view showing the relative position of the lock, bolt, tumbler bar and the release when withdrawn to permit free movement of the bolt member.

In the drawings showing one of the preferred constructions, the lock comprises a base 1, substantially rectangular in form, which preferably is made of suitable cast 30 metal. The base is provided with an opening 2 through which extends a plurality of tumbler members or bars 3, 4, 5, 6 and 7, which preferably may be of uniform, or if desired, identical construction, it being understood 35 that any desired number of tumblers may be provided, there being herein shown five for purposes of illustration.

Each of the tumbler members, in the preferred form, comprises rectangular bars having 40 a tapered surface 8 at one end thereof, the purpose of which will later be seen. The forward end of the tumblers slide within a keyhole housing 9 which is shown as a rectangular-shaped tube formed to embrace the 45 said tumbler members, there being provided at one end of the keyhole housing a flange 10, which is positioned about the edge of the opening 2 and is held in position on the base 1 by screws 11 or other suitable means.

50 The end of the keyhole housing 9 extends beyond the tapered end 8 of the tumbler members and forms a keyhole opening 12 in which longitudinally projecting ward members 13, 14, 15, 16 and 17, extending from a 55 key body 18, may extend the said ward members corresponding in number with the tumblers and engaging the corresponding tumbler members when the key is inserted in the keyhole 12.

60 In the preferred construction, there is provided for each one of the tumbler members a plurality of pegs 19, the bottom portion of said pegs being positioned in openings 20 of suitable shape spaced in the tumbler members; the said openings 20 and pegs 19 being

preferably cylindrical in form. If desired, the openings 20 may have conical shaped bottoms to facilitate the seating of the pegs, and the upper peg portion projecting above the tumbler bar may be, if desired, square 70 in form as shown in Figs. 9 and 10. Preferably the upper portion of the peg yet extending above the bar is of a larger dimension than the portion extending within the hole, this insuring that the portions of the pegs 75 extending above said bar will be of equal length. The pegs 19 are preferably positioned at the end of the tumbler bars.

Any suitable number of pegs may be used, but preferably the number of openings provided will exceed by three the number of tumbler members or the corresponding number of ward members for the key which are used. Further in the preferred form, the 80 number of pegs 19 provided will be two less 85 than the number of holes provided in the tumbler members, the purpose of which will later be seen.

In the positioning of the pegs 19, it is desirable that a peg be permanently positioned 90 in each of the end openings in each of the tumbler members, the one nearer the center of each of the tumblers coming in contact with the flange 10 of the keyhole housing 9 to limit the movement of the bars in one direction. The purpose of having the other 95 end peg permanently maintained in position will later be explained.

The ward members of the key 18 are positively held in the keyhole 12 by a projecting lip 21 carried by the key body forward of the end thereof, the said lip 21 engaging a slotted opening 22 positioned in one side of the keyhole housing. Each of the tumbler members is normally held in a forward 100 position with the peg 19 in contact with the flange 10 by a spring member 23 engaging the respective tumbler members.

The spring members in the preferred form are shown as flat leaf springs having one 110 end thereof engaging one end of the tumbler members, the other end of said spring 23 being fixed between two plate members 24, 25, which are held together by a screw 26 or other suitable connection. It is thus 115 seen that there is provided an independent spring member 23 for each of the tumblers, the said spring members functioning to push their tumblers to the foremost position wherein the tapered surfaces 8 will be in 120 alinement. The relative proportion of the various parts should be such as to permit at least one of the peg members to extend beyond the base 1, the reason for such a construction being later explained.

The upper edge of the plate member 24 is preferably formed to be in alinement with the top surface of the tumbler members and has a cut away portion to receive the tumbler members. In the preferred construc- 130

tion, the top edge further serves as a guide or rest on which a bolt or latch member 27 may ride.

In the preferred form, the bolt 27 is thus seen to move laterally or transversely of the tumbler members, the said bolt 27 being provided with a cut-out portion 28 forming the web portions 29, 30, the thickness of the web portion adjacent to the tumbler members being slightly less than that occupied by two adjacent pegs of the tumbler members or, in other words, the web 29 being of such a thickness as will permit said web to pass freely transversely of the tumbler members through a space or opening formed by the removal of adjacent pegs. It is understood, however, that the design of the various parts may be varied to meet the conditions of any particular case.

It is to be noted that the rearward movement of each of the tumbler members is limited and is the same, this movement being limited, in the preferred construction shown, by the engagement of the end peg 25 of the various tumbler members with the inner side of the web member 30 of the bolt 27. By providing a construction whereby each of the tumbler members have an equal movement when pressed rearwardly against the spring, it practically eliminates the possibility of an unauthorized person obtaining the combination of the lock and prevents the use of the usual master key. In other words, the effective positioning of the tumbler members to permit a movement of the bolt can in no way be determined by a movement of the various tumbler members to an extreme rearward position.

As a means of holding the bolt member of the lock normally against movement when the key is not inserted within the keyhole, one of the web portions 29 adjacent the inner end of the tumbler members is provided with a series of slots 31, the said slots being 45 of such a depth and thickness as to permit the peg members 19 to move therethrough, the number of slots in one series corresponding in number to the number of ward members having pegs therein. It is thus seen 50 that the pegs in the ward members extending within the slots 31 of the bolt prevent the movement of the bolt member.

It is now to be seen the importance of having at least one end peg in each of the 55 ward members, this being necessary in order that at least one peg of each of the ward members shall be positioned in each one of the series of slots when the key is not positioned in the keyhole. This is in order to 60 prevent the movement of the bolt until the key has properly positioned the tumbler members for such a movement.

Another series of slots 32 is provided in another part of the web 29 spaced from the 65 first-mentioned series of slots 31 by a space

ing portion 33, the second series of slots 32 also corresponding in number and size to the first series of slots 31, the respective series of slots 31 and 32 functioning to receive the pegs of the corresponding tumbler members 70 at the limits of movement of the bolt member 27.

In the preferred construction shown, preferably two adjacent pegs have been removed from each of the tumbler members, thus 75 leaving a space or pathway 34 therein of sufficient size to permit the web 29 to pass therethrough when in alignment therewith. The bolt 27 could not move until the space or pathway 34 of each of the tumbler members has been brought into alignment, with the web 29 or, in other words, until the space or path 34 of each of the tumbler members has been brought in alignment with the series of slots 31 or 32 depending upon 85 which series of slots is in alignment with the peg members.

In order that the spaces 34 may be brought into alignment with the key, the various tumbler members must be moved a 90 distance corresponding to the distance that the space 34 is positioned from the end of the tumbler members. For example, in Fig. 2 the tumblers 7, 6, 5, 4, 3 would have to be moved a distance corresponding to 4, 2, 3, 95 2, 4 pegs respectively and held in such a position, at which time the web 29 of the bolt 27 would then be free to move through the path formed by the aligned spaces 34 of the various tumbler members, as seen in 100 Fig. 4 showing the ward members 13, 14, 15, 16 and 17, extending within the keyhole and in contact with the tumbler members 7, 6, 5, 4, 3, respectively.

It is here to be noted that the setting of 105 the various ward members of the key corresponds to the setting of the pegs in the respective tumblers.

It is here to be further noted that if any one of the ward members of the key were 110 improperly set with reference to the positioning of the pegs in the tumbler member corresponding to such a ward member, it would be impossible to move the bolt 27, thus making it necessary that the exact setting or combination of the lock be known in order that the key may be set to correspond therewith.

As heretofore stated, the ward members projecting from the end of the key body 18 are held within the keyhole 12 in contact with the respective spring actuated tumbler members and is there positively held, in the preferred form shown, by the projecting lip 21 extending in the slot 22. The ends of the ward members have a tapered surface to correspond with the taper 8 at the end of the tumbler members, the taper being in such a direction as will keep the projecting lip 21 positioned in the slot 22. 125 130

In the preferred construction shown, the thickness of the ward members will be slightly less than the size of the keyhole 12, this being necessary in order to permit the 5 positioning of the projecting lip 21, but it is understood that any suitable means of holding the key in its effective position may be provided.

In the preferred construction shown, as 10 one means of limiting the movement of the bolt 27, there is provided a slotted opening 35 in the base 1, which is of a length corresponding to the movement desired of the bolt 27, the said bolt having a stud 36, the 15 stud 36 preferably being of such a length that the end thereof will extend through the slot 35 to the opposite side of the base 1, as shown in Fig. 1.

The bolt member may be automatically 20 actuated by a spring in one direction, if desired, and for this purpose there is provided a spring 37, which, in the preferred form, is set in a sunken portion 38 on one side of the base 1, one end of the spring being held 25 against movement and the other end engaging the stud 36 so that if the bolt 27 extends outward of the lock, as for example when the parts are in a locked position and the key is inserted within the keyhole to bring 30 the tumbler members so that the open paths 34 of each of the tumbler members will be in alinement with the web 29 of the bolt, the said bolt will be moved automatically inward of the lock by the spring 37. It is 35 thus seen that it requires only the insertion of the key without further movement thereof in order that the bolt may be withdrawn.

It is understood that any suitable spring 40 arrangement may be employed to effect movement of the bolt as the invention is not to be limited to the arrangement shown.

As a means of moving the bolt 27 when a spring is not used, the bolt is provided with 45 a toothed rack surface 39, shown in the drawings as being positioned on the upper edge of the bolt opposite to the positioning of the series of slots 31, 32, there being further provided a pinion 40 meshing with the 50 toothed rack 39, the said pinion being carried on a stem 41 extending through the base 1, so that one end thereof 42 extends outward of the main body of the lock so as to be in substantial alinement with the outer 55 edge of the keyhole housing 9, there being provided in the end of the said stem an opening 43 in which an instrument or key may be inserted in order that the pinion 40 may be rotated to move the bolt 27 in the desired direction. The key would be positioned within the keyhole in order to permit the free sliding movement of the bolt as actuated by the stem 41 through the pinion and rack connection, 40 and 39 respectively. 60 At each end of the lock 39 there is provided

a raised shoulder 44, which construction also serves as another means of limiting the movement of the bolt 27.

A suitable casing is provided for the lock which preferably comprises two parts, a 70 front cover or casing 45 and a rear cover or casing 46. The front cover or casing is provided with an opening through which the keyhole housing 9 extends and is provided with another opening to receive the stem 41, 75 there being provided about said opening a protective casing 47, which, in the preferred form, is shown integral with the front casing 45 and is tubular in form having the end thereof extending outwardly so as to be in 80 substantial alinement with the keyhole 12. The said protective casing 47 serves to prevent the stem from being damaged.

The front casing 45 is further provided with extending side portions 48, the said 85 front casing being held in position preferably by screws extending through the sides 48 and threaded in the base 1. The rear casing 46 is also provided with extending side portions 49 having the ends thereof butt 90 against the ends of the side portions 48 of the front casing, 45, the said rear casing 46 being held in position by a screw connection 50 extending through the side portion 49 and threaded in the base 1.

One of the side portions 50 is provided with a suitable opening 51 to receive the bolt 27. A portion of the inner surface 52 serves to position and guide one side of the bolt 27. A depressed portion 53 is provided on the 100 inside of the rear casing 46 so as to reduce the bearing surface between the bolt and rear casing. One end of the stem 41 is positioned in a boss 54 on the inner side of the rear casing 46.

If the lock is used in combination with the ordinary solid door jamb or bolt keeper and it is desired to move the bolt to a locking position, the key would first have to be inserted and the bolt 27 moved outwardly of the lock by actuating the pinion 40, after which the key would be withdrawn. If an automatically spring actuating bolt were provided in order to withdraw the bolt 27 from its locking position, it would only be necessary to 110 insert the key in the keyhole, at which time the bolt 27 would be automatically withdrawn and permit the door or other member to be opened.

A means is provided which will permit 120 the bolt 27 of the lock to be actuated without the use of a key, such for example from the inside of a hall door when the lock is used thereon. As a means of permitting such a movement of the bolt member, that 125 portion of the web 29 of the bolt 27 having the series of slots 31 and 32 thereon, is made movable with respect to the other mechanism of the lock so that the said portion, which we will call the release 55, may be 130

5 moved laterally of the bolt 27 or longitudinally of the tumbler members a distance sufficient to clear the end pegs of the tumblers when the tumblers are in what would be the normally locked position. In order to effect such a movement, a stem 56 is connected with the release 55 and extends outwardly of the lock casing through the web 30 of the bolt and through a slotted opening 10 57, which is formed in the rear casing 46 in order to permit the sliding movement of the bolt.

15 As a means of conveniently moving the release 55 and sliding the bolt, a suitable knob or handle 58 is secured to the projecting end of the stem 56 by a screw 59 or any other suitable means. The ends of the keeper 60, 61, and the top edge 62 of the keeper and the corresponding part of the 20 bolt in contact therewith are preferably tapered so as to accurately position the release 55 with respect to the bolt, the tumbler members, the pins and the pegs carried thereby. The accurate positioning of the release 25 55 is necessary in order that the pegs positioned in the tumbler members may pass freely through the series of slots 31 and 32.

30 As a means of maintaining the release 55 in a substantially parallel position with respect to the web portion 30 of the bolt, there are provided pins 63 having one end thereof spaced apart and fixed in the release 55 and the other end thereof extending through the web portion 30 of the bolt 27, and an 35 opening formed in a plate 64, which plate is also fixed to the web 30 of the bolt 27 to move therewith. The plate 64 is positioned within the slotted opening 57 of the casing 46.

40 As a means of holding the release 55 in position, there are provided springs 65, which, in the preferred form, are positioned about the pins 63, one end of the springs being in contact with the web 30 and the other end in contact with the release 55. It is thus seen that if the bolt is to be moved from inside the door without the use of the 45 knob 58, the knob 58 is grasped and pulled, which will withdraw the release 55 against a spring pressure out of the path of the end pegs of the tumblers and thus permit the bolt to be moved to the desired position by sliding movement of the knob 58. Fig. 14 shows the release withdrawn against the spring pressure in the direction of the arrows so that the said release 55 is withdrawn from the path of the pegs 19 positioned at the end of the tumbler.

50 With reference to the arrangement of the casing it is understood that any suitable construction may be employed for covering the working parts of the lock.

55 It is further to be understood that the lock may be adapted for various uses including interior and out-of-doors, safes, padlocks,

etc. In the positioning of the lock it is preferably so arranged that the keyhole housing 9 and protective casing 47 will be embedded in wood, metal or other material 66, as shown in Fig. 5.

70

If, for example, the lock is used with a solid door jamb on an outside door either with or without the spring 37, and it is desired to lock the door from the outside and if the person is indoors and desires to go 75 out-of-doors and then lock the door, it would first be necessary to release the bolt 27 by withdrawing the knob 58, thus moving the release 55 out of the path of the end peg members 19 and moving the bolt to a 80 withdrawn position when the door may be opened. In order to lock the door in the assumed case with the solid door jamb, it would be necessary to insert the key in the keyhole from the outside and then move the 85 bolt to a locked position by moving the bolt through the stem 41 and pinion 40 engaging the toothed surface 39, after which the key would be withdrawn.

90 In order to eliminate the necessity for either withdrawing the bolt through the release from the inside and for inserting the key from the outside and turning the bolt through the pinion connection, there has been provided what may be termed the 95 spring slide or keeper for the lock. The said spring slide or keeper is positioned on the door jamb and eliminates the necessity of having to withdraw the bolt from inside in order to open or close the door.

100

105 In the preferred construction shown, the spring slide door jamb or keeper comprises a rectangular box-like casing 67 open at one end 68 and the top 69 thereof. A cover 70 for the casing is provided, which, in the preferred form, has flanges 71 on either side thereof guided in grooves 72 formed in the upper edge of the sides of the casing 67.

110 In the construction shown, the cover 70 is provided with a projection 73, there being 115 provided a compression spring 74, positioned between said projection and one end 75 of the casing so that the said spring will normally tend to keep the cover 70 closed. As a means of assisting in positioning the 115 ends of the spring 74, there are provided studs 76 positioned in the projection 73 and one end of the casing 75.

120 At the end of the spring slide door jamb adjacent the door, there is provided an L-shaped spring member 77 having one end thereof extending around the bottom edge of the casing and there suitably secured. One of the legs 78 of the L-shaped member extends inward from the end of the casing a distance substantially equal to the distance which the bolt member 27 projects from the lock, and the other leg 79 of the L-shaped portion is of a length substantially equal to the width of the bolt 27, there being pro-

vided in the sides of the casing grooves 81, in which the edges of the leg 79 are positioned to be guided therein.

- 5 A spring 80 is positioned in a recess in the bottom of the casing under one leg of the L-shaped member so that when the cover 70 is withdrawn a sufficient distance substantially equal to the length of the projecting bolt 27, and the bolt is moved outwardly of the casing, the spring 80 will move the L-shaped member outwardly of the casing so that the upper end of the leg 79 will be moved outwardly so as to come within the path of movement of the cover 70 and will hold the 10 said cover in an open position against the action of the spring 74 until the door is again closed and locked, at which time the bolt 27 will be moved inwardly of the casing and will strike the leg 78 of the spring member, thus withdrawing the outer end of the leg 79 from its holding position with respect to the top 70 and permit the spring 74 to move the top 70 to a closed position over the bolt.
- 15 25 A knob or handle 82 is secured by suitable means to the top sliding cover 70 so that if it is desired to open the door from the inside without the use of a key or removing the release of the lock, it is only necessary to grasp the handle 82 and withdraw the cover 70 from the casing a sufficient distance to permit the bolt 27 to move freely out of the casing. If, with the parts in this position, it is desired to have the door unlocked when 20 30 35 passing outside, it is only necessary to pass out and close the door, at which time the bolt 27 will move within the casing and release the spring-actuated cover 70. It is thus seen that by providing a spring-actuated sliding door jamb, it is not necessary to use a key at any time in passing from within to the outside. The said sliding door spring door jamb is to be the subject of a 40 separate application.
- 45 It is thus seen that there is herein provided a combination lock of simple construction having relatively few parts so arranged that by the insertion only of a combination key in the keyhole of the lock, the tumbler members are directly actuated by the ward members of the key and are moved longitudinally of the keyhole thereby, thus positioning an adjustable means carried by the tumbler members so as to permit free movement of the bolt, which may be either automatically spring actuated in one direction or may be positively manually moved in each direction from one side. Further, the bolt may be provided with a release member 50 55 60 65 adapted to be actuated from the side of the lock opposite to that to which the key is applied so that the said bolt may be freely moved without the necessity of having to use a key.
- 65 Attention is here called to a very impor-

tant feature of the construction, which mainly is the provision of an adjustable means coöperating with each one of the tumbler members by which the combination of the lock may be changed, such a 70 means including herein the provision of a plurality of interchangeable peg members for each of the tumbler members.

If it is desired to use a lock embodying the adjustable combination feature, certain 75 portions of the lock shown may be omitted, such as the release member and the spring member for actuating the bolt.

It is further to be noted that if the combination lock, having the automatic spring 80 for actuating the bolt in one direction, is used as a hall or outside door lock in combination with the sliding spring door jamb, the pinion, stem and protective casing may be dispensed with.

85 While but one preferred construction has herein been shown, it is understood that various changes and modifications may be made without departing from the spirit and scope of this invention as set forth in the 90 claims.

95 The specific keeper shown and described herein is claimed broadly in my copending application Serial No. 306,784, filed June 26, 1919, and the key shown and described in this application is claimed broadly in my copending application Serial No. 328,170, filed October 3, 1919.

Having thus described the invention, what I claim as new is:

100 1. In a combination lock, comprising a plurality of tumbler members and a bolt arranged to move transversely of said tumbler members, an adjustable means including a plurality of independently movable members carried by the tumblers and arranged thereon to normally prevent movement of said bolt.

105 2. In a combination lock, comprising a plurality of tumbler members and a bolt arranged to move transversely of said tumbler members, an adjustable means including a plurality of independently movable members carried by the tumblers and arranged thereon to normally prevent movement of said bolt, but said means being positioned to permit movement of the bolt transversely of the tumbler members upon a predetermined movement of the tumbler members.

110 3. In a combination lock, comprising tumbler members and a bolt arranged to move transversely of the tumbler members, an adjustable means including a plurality of independently movable members arranged on said tumbler members normally restraining movement of said bolt, said means being arranged to permit a free sliding movement of the bolt when the tumbler members have received a limited movement.

130

4. In a combination lock, comprising tumbler members and a bolt arranged and adapted to be moved laterally of said tumbler members, an adjustable means including a plurality of independently movable members carried by said tumbler members and arranged normally in the path of movement of said bolt, the said means being arranged to permit free movement of the bolt after the tumbler members have been moved a certain distance.

5. In a combination lock, comprising tumbler members and a bolt arranged and adapted to be moved laterally of said tumbler members, an adjustable means including a plurality of independently movable members carried by said tumbler members and arranged normally in the path of movement of said bolt, the said means being arranged to permit free movement of the bolt after the tumbler members have been moved a certain distance, said means being adjustable on said tumbler members to vary the movement required of the respective tumbler members in order to permit free movement of the bolt.

6. A combination lock, comprising spring-actuated tumbler members, a bolt arranged for movement transversely of the tumbler members, a release carried by said bolt, a means arranged on said tumbler members normally in the path of movement of said release, and a means for moving said release out of the path of movement of said first-named means to permit movement of the bolt.

7. A combination lock, comprising a plurality of tumbler members, a bolt arranged for movement transversely of said tumbler members, a spring actuated release carried by said bolt, said release including a series of slots thereon, and means arranged on said tumbler members normally in the path of movement of said release to prevent movement thereof, the said means including pegs, the pegs on the tumbler members being arranged to form an open path through which the release may pass when the tumbler members have been moved a predetermined distance.

8. In a device of the character described, a combination lock comprising a bolt, tumbler members, and a means including a plurality of relatively movable elements coöperating with each tumbler member, one of said elements being normally positioned in the path of movement of said bolt.

9. In a device of the character described, a combination lock comprising a bolt, tumbler members, and a means coöperating with said tumbler members normally positioned in the path of movement of said bolt, said means including a plurality of peg members adapted to be adjustably positioned on said tumbler members so as to permit movement

of the bolt transversely of the tumbler members at different points of said tumbler members, said points being dependent upon the movement of the tumbler members and the positioning of said means upon the tumbler.

10. A combination lock comprising a plurality of tumbler members, a bolt arranged for movement transversely of said tumbler members, and adjustable means including relatively movable elements coöperating with the tumbler members and movable therewith, one of said elements being arranged to normally restrain the bolt against movement but permitting movement of the bolt upon a predetermined movement of the tumbler members.

11. A combination lock comprising a bolt, spring-actuated tumbler members movable transversely of the bolt, and means including a plurality of relatively movable elements carried by each of the tumbler members adjustably to permit free movement of the bolt when the said tumbler members have been moved a predetermined distance, certain of said elements on each tumbler being arranged to limit the movement of the tumbler in one direction.

12. A combination lock comprising a bolt, tumbler members, and adjustable means including a plurality of independent relatively movable elements coöperating with said tumbler members to normally restrain the bolt member against movement, the movement of said bolt being dependent upon the relative positioning of the means coöperating with the tumblers and the movement of the tumbler members, certain of said elements being arranged at the same relative position on each tumbler to limit the movement thereof in each direction.

13. A combination lock comprising a base, having an opening therein, a plurality of spring-pressed tumbler members extending through said opening, a bolt movable transversely of the tumblers, means for guiding said bolt adjacent one end of the tumbler members, a plurality of pegs positioned in each tumbler member so as to form an open pathway between certain of said pegs, and slots in said bolt to receive pegs of the tumbler members, the said pegs being normally positioned in said slots to hold the bolt against movement, the said tumbler members, the pegs thereon and the slotted portion of the bolt being arranged to permit movement of the bolt when the tumbler members are moved so that the open pathway formed by the pegs are in alignment with the portion of the bolt forming slots therein.

14. A combination lock comprising a bolt, tumbler members movable laterally of the bolt, a web portion carried by said bolt having slots therein, said slots being in substantial alignment with the tumbler mem-

- bers, and means carried by said tumbler members normally positioned in said slots to prevent movement of the bolt, said means including a plurality of pegs arranged on the 5 tumbler members, certain of said pegs being spaced to form an opening therebetween of a width sufficient to permit the passage of the web portion of the bolt therethrough, said tumbler members in said bolt being arranged to permit free movement of the bolt 10 when the tumbler members have been moved so that the space between adjacent peg members are in substantial alinement with the web member of the bolt.
- 15 15. In a combination lock, adapted to be actuated by a combination key, comprising a bolt and tumbler members movable transversely thereof, adjustable means including a plurality of relatively movable elements 20 spaced on each of said tumbler members normally restraining the bolt against movement, the said tumblers being arranged with respect to the bolt so that when the key is inserted in said lock, the said means is 25 brought into alinement to permit free movement of the bolt, certain of said elements being placed on the tumblers at the same relative position to each tumbler to limit the movement of the tumbler in each direction.
- 30 16. In a combination lock comprising a bolt and a plurality of tumbler members movable transversely thereof, an adjustable means including a plurality of relatively movable elements cooperating with the tumbler members for normally restraining the bolt against movement, said means being arranged to permit free movement upon a limited movement of the tumbler members, certain of said elements being arranged on the 35 tumblers to permit the same limit of movement on the tumblers.
- 40 17. A combination lock comprising a base, having a rectangular-shaped opening therein, a keyhole housing secured to said base embracing a part of said opening and extending outwardly of said base, a plurality of tumbler members of uniform construction 45 slidable in said housing having one end thereof positioned in said housing and the other end thereof extending rearwardly of the base, the said tumbler members having a series of openings therein extending inwardly from the projecting end thereof, pegs positioned in some of said 50 openings, the end openings having pegs permanently positioned therein, a spring member for the tumblers positioning said tumblers so that at least one peg will extend rearwardly of the base, and a bolt having a 55 slotted web arranged for movement transversely of the tumbler members, the said projecting peg of the tumbler members being normally positioned in the slotted portion of the web to prevent movement of the bolt member, the pegs on each of the tum- 60 bers, and means carried by said tumbler members normally positioned in said slots to prevent movement of the bolt, said means including a plurality of pegs arranged on the 65 tumbler members, certain of said pegs being spaced to form an opening therebetween of a width sufficient to permit the passage of the web portion of the bolt therethrough, said tumbler members in said bolt being arranged to permit free movement of the bolt when the tumbler members have been moved so that the space between adjacent peg members are in substantial alinement with the web member of the bolt.

bler members being so positioned that when each of the tumbler members have been moved a predetermined distance, the openings of the tumbler members which are not provided with pegs will be in alinement with the slotted web portion of the bolt so that the bolt may be freely moved.

18. A combination lock comprising a base, having a rectangular-shaped opening therein, a keyhole housing secured to said base embracing a part of said opening and extending outwardly of said base, a plurality of tumbler members of uniform construction slidable in said housing having one end thereof positioned in said housing and the other end thereof extending rearwardly of the base, the said tumbler members having a series of openings therein extending inwardly from the projecting end thereof, pegs positioned in some of said openings, the end openings having pegs permanently positioned therein, a spring member for the tumblers positioning said tumblers so that at least one peg will extend rearwardly of the base, a bolt having a slotted web arranged for movement transversely of the tumbler members, the said projecting peg of the tumbler members being normally positioned in the slotted portion of the web to prevent movement of the bolt member, the pegs on each of the tumbler members being so positioned that when each of the tumbler members have been moved a predetermined distance, the openings of the tumbler members which are not provided with pegs will be in alinement with the slotted web portion of the bolt so that the bolt may be freely moved.

19. A combination lock comprising a bolt having a slotted web, spring-pressed tumbler members of identical size and form movable transversely of said bolt, and a means including a plurality of adjustable elements carried by each of said tumblers normally positioned in the slots of said web portion preventing movement of said bolt, the ends of said tumbler members being normally in alinement and extending in a keyhole housing so as to come in direct contact with a key inserted in said keyhole so that the tumbler members will be moved longitudinally and bring the said means out of alinement with the slotted web portion of the bolt to permit movement of said bolt transversely of the tumbler members.

20. A combination lock comprising a bolt having a slotted web, tumbler members movable laterally of the bolt, means carried by the tumblers normally positioned in the slots of the web portion to prevent movement of the bolt, and a means connected with the bolt for moving the said slotted

web portion transversely of the bolt out of alinement with said first named means to permit free movement of said bolt.

21. A combination lock comprising a bolt 5 having a slotted web portion, a plurality of tumbler members, and a plurality of peg members carried by said tumbler members, certain of said pegs being normally positioned within the slotted portion of the bolt 10 to prevent movement thereof, the position of the pegs in the said tumbler members being adjustable to require different movements of the tumbler members in order to permit free movement of the bolt.
22. A combination lock comprising tumbler members, adjustable means including relatively movable elements associated therewith, and a bolt movable relative to the tumbler members, the movement of the bolt 20 relative to the tumbler members being dependent upon the position of the means associated with the tumbler members relative thereto, and the movement of the tumbler members, certain of said elements being 25 arranged on the tumblers to limit the movement thereof in each direction.
23. A combination lock comprising a bolt, tumbler members, and means including relatively movable elements carried by the 30 tumbler members and adjustable relative thereto, the movement of the bolt being dependent upon the positioning of the adjustable means associated with the tumbler, certain of said elements being arranged to

limit the movement of the tumblers in one 35 direction.

24. In a combination lock, comprising tumbler members and a bolt, a means including relatively movable elements carried by each of the tumbler members and adjustable relative thereto for determining the movement of the tumblers necessary to permit the movement of the bolt. 40

25. In a device of the character described the combination of a lock having a sliding bolt, a spring slide door jamb to receive the bolt, the slide being movable in the same direction as the bolt and a release device actuated by the bolt, for holding the spring slide in a withdrawn position. 45

26. In a device of the character described, a tumbler, and a plurality of independently movable elements adjustable thereon. 50

27. The combination of a bolt, tumbler members movable relative thereto, and means including a plurality of adjustable elements carried by said tumblers for determining the movement of said bolt. 55

28. The combination of a bolt, tumbler members movable relative thereto, a means including a plurality of elements adjustable on said tumblers, normally restraining the bolt against movement, and a release carried by the bolt and adapted to be moved out of alinement with the said last named means. 60 65
